UNITED STATES PATENT OFFICE.

ARTHUR H. DRUCKEY, OF CHICAGO, ILLINOIS.

SUPERVAPORIZER.

Application filed May 29, 1923. Serial No. 642,313.

To all whom it may concern:

Be it known that I, ARTHUR H. DRUCKEY, a citizen of the United States, residing at Chicago, in the county of Cook and State of Illinois, have invented certain new and useful Improvements in Supervaporizers, of which the following is a specification.

The present invention relates to a super-vaporizer designed for use upon internal combustion engines. With the use of liquid combustible fuel such as gasoline, when first starting and until the engine is thoroughly heated, the raw fuel passes into the cylinders of the engine which not only produces carbon but thins the lubricating oil on the cylinder walls and passes to the crank case and dilutes the oil contained therein. The engine also frequently misses when cold. To heat the mixture and provide complete combustion immediately upon starting the engine is the principal purpose of the present super-vaporizer. To accomplish this the super-vaporizer construction allows hot gases from the exhaust manifold to be drawn directly into the intake manifold, thus the heat of the burnt gas from the exhaust changes the wet, poorly carbureted mixture into a dry vapor which combusts with full efficiency when it is ignited by the spark in the explosive chamber of the cylinder. As the motor warms up a thermostatically operated valve of the super-vaporizer is closing and will finally become fully closed when the engine is thoroughly warm. After the passage of the hot exhaust gases into the intake manifold is fully stopped, air is taken in through a breather valve and will be heated by this device and drawn into the intake manifold, producing an economical combustible mixture. This allows the engine to be started immediately particularly in cold weather and prevents dilution of the engine oil.

Another important object of the invention is to provide a super-vaporizer of this nature having a simple and efficient construction, one which is reliable, inexpensive to manufacture, durable, and well adapted for the purpose for which it is designed.

With the above and other objects in view as will appear as the description progresses, the invention resides in certain novel features of construction, and in the combination and arrangement of parts as will be hereinafter more fully described and claimed.

In the drawing:

Figure 1 is a front elevation of the device showing the same associated with an intake manifold and an exhaust manifold, 60

Figure 2 is a front elevation of the device with the cover plate removed,

Figure 3 is a plan view of the inner side of the cover plate,

Figure 4 is a vertical section taken substantially on the line 4—4 of Figure 1, 65

Figure 5 is a section taken substantially on the line 5—5 of Figure 4 looking in the direction of the arrow, and

Figure 6 is an end elevation of an engine 70 with my device attached thereto showing a modification wherein the exhaust manifold is upon the opposite side of the engine to that of the intake manifold.

Referring to the drawing in detail it will be seen that 1 designates an exhaust manifold and 2 an intake manifold of any desired construction. The super-vaporizer consists of a casing 3 having one end opened and closeable by a plate 4. A plate 5 forms a partition in the casing 3 forming compartments 6 and 7. This partition 5 is provided with an opening 8 and an opening 9 which are preferably disposed adjacent each other. A shaft 10 is journalled at one end in the rear wall of the casing 3 and passes centrally through the partition 5. A plate valve 11 is keyed to the shaft 10 by means of a set screw 12 or in any other suitable manner and is disposed to operate within the compartment 6 for closing the opening 8. This valve 11 is thermostatically operated and a thermo-responsive means 13 is disposed within the compartment 7 and consists of a bi-metal coil preferably brass and steel, 85 other metals however, may be used. One end of the thermo-responsive means is attached to the shaft 10 and the other end suitably attached to the partition 5. A slotted lug 14 is mounted in the partition 5 and receives the last mentioned end of the thermo-responsive means and the same is held therein by means of a set screw 15. At ordinary atmospherical temperature, the thermo-responsive means holds the shaft so that the 90

plate valve 11 is not disposed opposite the opening 8. Suitable communicating means 17 is attached to the exhaust manifold 1 and enters the compartment 6 preferably at the upper end of the device. Suitable communicating means 18 is attached to the intake manifold 2 and communicates with the 95 100 105 110

compartment 7. This latter means preferably includes a nipple which is threaded through the back wall of the casing 3 and into the opening 9 of the partition 5.

5 The closed plate 4 is held in engagement with the casing 3 by screws 19 or other means and these screws preferably threadedly engage the partition 5. A breather valve 20 is mounted on the plate 4 so as to communicate with compartment 7 and includes a casing having a spring pressed valve 21 therein.

When the engine upon which this device is located is started the exhaust gases will 15 pass through the communicating means 17 into the compartment 6, through opening 8 and fill compartment 7 and then pass through the communicating means 18 into the intake manifold. The exhaust gases 20 being heated will act upon the thermo-responsive means 13 tending to expand the same and rotate the shaft 10 so as to hold the plate valve 11 over the opening 8. When this opening 8 is completely closed, air will 25 be drawn through the breather valve 20 into compartment 7 and pass through the communicating means 18 into the intake manifold. It will be noted that the partition 5 is at all times thoroughly heated by the 30 exhaust gases in compartment 6 and this heat will be imparted to the air passing through compartment 7.

I have, in the present instance, shown and described the preferred embodiment of 35 the super-vaporizer which will give in practice satisfactory and reliable results, and it is to be understood that the same are susceptible of modifications in various particulars without departing from the spirit or 40 scope of the invention or sacrificing any of its advantages.

Having thus described my invention what I claim as new and desire to secure by Letters Patent, is:

- 45 1. A device of the class described including a casing having a pair of compartments formed therein, said compartments communicating with each other, a thermo-responsive mechanism for closing the communication between the compartments, means for communicating one compartment with an exhaust manifold of an internal combustion engine, and the means for communicating the other compartment with an intake manifold of an internal combustion engine, a breather valve associated with the latter mentioned compartment, and a spring 50 associated with said breather valve and tensioned so as to hold the same closed when the communication between the two compartments is open.
- 55 2. A device of the class described including a casing, a partition in the casing forming two compartments therein, said parti-

tion provided with an opening, a thermostatically controlled valve associated with said partition for closing said opening therein, one compartment adapted to be communicated with the exhaust manifold of an internal combustion engine, the other compartment adapted to be communicated with the intake manifold of an internal combustion engine, a breather valve associated with the latter compartment, and a spring associated with the breather valve for normally holding the same closed when the opening in the partition is open and allowing the breather valve to open when said opening in the partition is closed by the thermostatically controlled valve.

3. A device of the class described including a casing, a partition in the casing forming two compartments therein, said partition provided with an opening communicating these two compartments with each other, a valve disposed within one compartment for closing said opening in said partition, a shaft journalled through the compartment for operation of said valve, a thermo-responsive means in the other compartment for operating said shaft, and a breather valve associated with the last mentioned compartment, said last mentioned compartment adapted to be communicated with the intake manifold of an internal combustion engine and the other compartment adapted to be communicated with an exhaust manifold of an internal combustion engine.

4. A device of the class described including a casing, a partition in the casing forming two compartments therein, one of said compartments adapted to be communicated with the exhaust manifold of an internal combustion engine, the other compartment adapted to be communicated with the intake manifold of an internal combustion engine, said partition provided with an opening, a valve in the exhaust compartment adapted to close said opening, a shaft passing through the partition for operation of the valve, thermo-responsive means of the shaft within the intake compartment, said means including a bi-metal coil attached at one end to the shaft, a lug passing through the partition, means for attaching the other end of the coil to the lug, said lug projecting into the exhaust compartment acting as a stop for said valve when closed over the opening in the partition, and a breather valve associated with the intake compartment.

In testimony whereof I affix my signature in presence of two witnesses.

ARTHUR H. DRUCKEY.
